UNITED STATES PATENT OFFICE

GEORGE W. BUTLER, OF KNOXVILLE, TENNESSEE, ASSIGNOR OF ONE-HALF
TO WILLIAM B. SHOEMAKER, OF SAME PLACE.

CAR-COUPING.

SPECIFICATION forming part of Letters Patent No. 268,386, dated December 5, 1882.

Application filed July 15, 1882. (No model.)

To all whom it may concern:

Be it known that I, GEORGE W. BUTLER, of Knoxville, in the county of Knox and State of Tennessee, have invented certain new and 5 useful Improvements in Car-Couplings; and I do hereby declare that the following is a full, clear, and exact description of the invention, which will enable others skilled in the art to which it appertains to make and use the same, reference being had to the accompanying drawings, which form a part of this specification.

Figure 1 is a perspective view of my improved car-coupling. Fig. 2 is a longitudinal vertical sectional view. Fig. 3 is a side view, 15 and Fig. 4 is a top view.

Corresponding parts in the several figures are denoted by like letters of reference.

This invention relates to that class of car-couplings which operate automatically when 20 the cars come together; and it consists in certain improvements in the construction of the same, which will be hereinafter fully described, and particularly pointed out in the claims.

In the drawings hereto annexed, A represents the draw-head, which is provided at its 25 front end with a V-shaped horizontal slot or opening forming the mouth, and surrounded by a frame or flange, B.

C is a vertical slot, extending through the 30 entire length of the draw-head.

D is the coupling-pin, which is pivoted upon a pin, E, in the slot C, just above the mouth of the draw-head. Said pin or "lever," as it might be termed, has a curved arm, G, which 35 is provided with a notch, F, in its front side. The rear side of the arm G is separated by a recess, H, from the plate or body I of the lever, which is weighted, so that when the pin is released or uncoupled the said plate I shall 40 swing down and hold the arm G in a horizontal position. The front side of plate I is beveled, as at J.

K is a lever, pivoted in the slot C near the front end and below the mouth of the draw-head. Lever K has a tooth, L, to engage the 45 notch F of the coupling-pin; and a spring, M, is arranged, as shown, to force lever K upward, in order to effect such engagement automatically.

N is a rock-shaft, mounted transversely in a 50 draw-head and having an arm, O, adapted to bear downwardly upon the rear end of lever K, and thus release the latter from the coupling-pin. Shaft N has at one end a crank, P, from which a connecting-rod, Q, extends to 55 the top of the car, from which said shaft may be operated, for the purpose of uncoupling, by simply raising the connecting-rod Q. By depressing the connecting-rod Q, the rock-shaft N is turned in the opposite direction, thereby 60 raising the arm O and bringing it in contact with an arm, R, extending forwardly from a transverse shaft, S, mounted in the draw-head.

To the ends of shaft S, which extend beyond the sides of the draw-head, are attached the 65 ends of a bail, T, projecting forwardly into the mouth of the draw-head, where a transverse groove, U, is provided for its accommodation. When the connecting-rod Q is depressed, as stated, the bail T is raised, thus 70 raising the coupling-link which has been previously inserted into the mouth of the draw-head, and enabling it to engage the draw-head of an adjoining car of any height.

The rock-shaft N may also be operated by 75 means of a crank, U', at its opposite end. Said crank is connected, by a rearward-extending pivoted rod, Y, with a hanger, V, pivoted under the body of the car.

W is a lever, pivoted to the side of the car 80 and working in a slot, X, in rod Y, which may be thereby manipulated, thus operating the rock-shaft N.

The operation of my invention will be readily understood from the foregoing description, 85 taken in connection with the drawings hereto annexed. It is simple, convenient, and may be easily operated without the necessity of going between the cars.

I claim and desire to secure by Letters Patent of the United States—

1. The combination, with the draw-head A, having mouth B and slot C, of the pivoted coupling pin or lever D, having curved arm G, provided with notch F, recess H, and plate 90 or body I, having beveled front side, J, and the lever K, having tooth L and spring M, as set forth.

2. The combination, with draw-head A, having mouth B and slot C, of the pivoted coupling-pin D, the lever K, having tooth L, spring M, and the rock-shaft N, having arm O, as set forth.

3. The combination, with the draw-head A, having mouth B and slot C, of the pivoted coupling-pin D, lever K, having tooth L, spring M, shaft S, having arm R, and bail T, and the rock-shaft N, having arm O, as set forth.

4. The combination of the draw-head A, having mouth B and slot C, the pivoted coupling-

pin D, lever K, having tooth L, spring M, shaft S, having arm R, and bail T, rock-shaft N, having arm O and crank U', pivoted rod Y, having slot X, hanger V, and lever W, substantially as and for the purpose set forth. 15

In testimony that I claim the foregoing as my own I have hereunto affixed my signature in presence of two witnesses.

GEORGE W. BUTLER.
